UNITED STATES PATENT OFFICE.

LYSANDER H. DODGE, OF HUNTINGTON BEACH, CALIFORNIA.

FOLLOWER BLOCK FOR FILING DRAWERS.

Application filed July 30, 1925. Serial No. 46,976.

This invention has to do with follower blocks for filing drawers, card index trays and the like, and it is the general object of the invention to provide a superior device of this character, both as regards simplicity and general efficiency.

It is, of course, essential that follower blocks be movable longitudinally of filing compartments and held firmly in adjusted position. Yet the holding means must be of a nature to be readily and easily released, as is well understood. Heretofore, so far as I am aware, in order that follower blocks may have the desired characteristics, it has been necessary to prepare filing drawers or trays especially for their reception. For instance, rods are used which extend longitudinally of the receptacle and pass through frictional binding clamps on the follower; there have been ways extending longitudinally of the receptacle and taking flanges of the followers; and there have been provided horizontally spaced, vertically extending grooves in the sides of the receptacles and adapted to take anchoring tabs or flanges which extend from the follower block, proper. So preparing the filing drawers are, of course, matters of considerable labor and expense, and it is therefore an object of the present invention to provide a block which may be used in any drawer (within reasonable limits) without in any way altering said drawer by addition or mutilation. The economic advantages of this feature are self evident.

As further features, the block is so constructed that it may be used in connection with either wood or metal filing drawers, and may be extended or contracted to fit operatively within drawers of different widths. The block may also be adjusted to extend vertically or incline forwardly or rearwardly, such inclination being very desirable in certain situations.

Yet with all these possible adjustments, the releasable holding means is of a character to hold the block firmly in set position.

Other objects and novel features will be apparent from the following detailed specification, reference being made to the accompanying drawings, in which:

Fig. 1 is a fragmentary, top plan view of a drawer within which one of my follower blocks is disposed;

Fig. 2 is a view of Fig. 1 looking in the direction of arrow 2;

Fig. 3 is a view generally similar to Fig. 2, but showing the block installed in a metal drawer of greater width than the drawer shown in Fig. 2;

Fig. 4 is an enlarged vertical section on broken line 4-4 of Fig. 2;

Fig. 5 is an enlarged horizontal section on line 5-5 of Fig. 2;

Fig. 6 is an enlarged fragmentary section on line 6-6 of Fig. 3; and

Fig. 7 is a view showing how the block may be supported in an inclined position and clear of the drawer bottom.

In Figures 1 and 2, I have shown the rectangular block 10 disposed transversely in a wooden drawer having sides 11 and bottom 12. I will describe the block as being made of metal and as being longitudinally extensible, but it will be understood that it lies within the scope of my broader claims to substitute other material and to make the block, proper, of a single, non-extensible piece.

Block or body member 10 is made up of two telescopically arranged or relatively longitudinally slideable plates 14 and 15. Plate 14 is preferably of double thickness, its walls being spaced apart to receive plate 15 slidably between them. One wall of the tubular plate is cut away at one end 17 to accommodate the clamping apparatus (to be described) on plate 15, but such of the metal as is left at this cut-away end overhangs upper and lower edges of plate 15 at 18 and may be termed keeper or way defining flanges. A limiting stop 19 extending through plate 14 may be adapted to engage shoulder 20 of plate 15 to limit the relative contractive movement of the plates; while set screws 21 may be threaded through one wall of plate 15 or flanges 18 and into contact with plate 14 to hold the plates releasably in adjusted position.

It will be evident how screws 21 may be loosened to allow the body member to be extended or contracted to fit drawers of different widths. Thus in Fig. 3 the block is shown extended to fit metal drawer M which is wider than the wooden drawer indicated in Figs. 1 and 2.

Plates 14 and 15 each have a clamping device thereon, but since these devices may be identical, I will describe but one in de-

tail. An angularly bent arm 22 is secured in any suitable manner (by soldering for instance) to vertical rod 23, the latter being rotatably supported on its associated plate 5 by brackets 24. The arm is preferably secured to the rod about at the point of its bend, and the end portions 23a of the rod which have bearing in brackets 24 may be of reduced diameter in order to provide annular shoulders 25 which coact with the brackets to limit the vertical movement of the rod with respect to the block plate.

The outer end of each arm 22 is forked, thus providing two or more vertically aligned bearing points 26, 27 and the arm is of such length that when it is swung upon its vertical axis towards the plate and into about the full line position of Fig. 1, the bearing points extend beyond the end of the block and into engagement with the side wall of the drawer. A spring 28 is coiled about rod 23 and its free ends 29 and 30 engage plate 15 and angular extension 31 of the arm, respectively, so as always to tend to swing the forked end of the arm towards the block. Angular extension 31 provides a hand-hold whereby the operator may reach over the top of the block and press the horizontally spaced extension towards the block and thereby swing the forked end of the arm into the dotted line position of Fig. 1, this against the action of spring 28.

With the two plates similarly equipped with arms 22, it will be seen that springs 28 normally hold the two sets of bearing points 26, 27 in pressural engagement with the opposite side walls of the drawer and serve to hold the block from displacement. Extensions 31 need only be pressed toward the block to swing the arms inwardly and thereby free the bearing points from side walls 11 so the block may be shifted longitudinally of the drawer.

Due to the four point engagement of the arms, the block may be tilted at any angle, for instance, as shown in Fig. 7 and it may even be supported so its lower edge is clear of the drawer bottom.

In order that the body member may not unduly tilt horizontally about one or the other of rods 23 when in applied position, I may provide adjustable stops 32. These stops are illustrated as screws threaded through arms 22 and locked in adjusted position by jamb nuts 33, though, of course, the screws may, in some situations, be supported by the body member and have their free ends adapted to be engaged by the arms. The stops may be considered as adjustable means for limiting the pivotal movement of the arms in their spring-urged direction, and it will be seen that they prevent the arms from being swung into parallelism with the body member.

When the follower is used in connection

with metal drawers, I prefer to provide shoes 34 on bearing points 26, 27. These shoes may be rubber "vacuum cups" 35 (Fig. 6) held within sockets 36 which are fastened to plates 14, 15 at 37. It will be readily understood that shoes of this type will grip the metal drawer walls much more effectively than bare points.

It will be understood the drawings and description are to be considered merely illustrative of and not restrictive on the broader claims appended hereto, for various changes in design, structure and arrangement may be made without departing from the spirit and scope of said claims.

I claim:

1. In a device of the character described, a block adapted to extend across a file compartment, a pair of gripping arms adapted to extend beyond opposite edges of the block and mounted thereon for pivotal movement about axes which are substantially parallel with the block, springs applied to the arms and adapted to swing them pivotally in opposite directions, and adjustable means acting between said arms and block adapted to limit the extent of pivotal movement of said arms in said directions.

2. In a device of the character described, a block adapted to extend across a file compartment, a pair of gripping arms adapted to extend beyond opposite edges of the block and mounted thereon for pivotal movement about axes which are substantially parallel with the block, springs applied to the arms and adapted to swing them pivotally towards the block, stops extending from the arms towards the block and adapted to engage said block to limit the extent of pivotal movement of said arms there-towards.

3. In a device of the character described, a block adapted to extend across a file compartment, a pair of gripping arms adapted to extend beyond opposite edges of the block and mounted thereon for pivotal movement about axes which are substantially parallel with the block, springs applied to the arms and adapted to swing them pivotally towards the block, screws threaded through the arms towards the block and adapted to engage said block to limit the extent of pivotal movement of said arms there-towards.

4. A follower block for a filing drawer, embodying a pair of rectangular plates in and extending transversely of the drawer, said plates being adapted to slide longitudinally towards and away from one another, means on the two plates adapted to coact in a manner to hold them against lateral separative movement, releasable means for holding the two plates against relative longitudinal movement, and means on the plates adapted to engage the side walls of the drawer releasably for holding the follower in predetermined position within the drawer.

5. A follower block for a filing drawer, embodying a pair of telescopically arranged plates, in and extending transversely of the drawer, releasable means for holding the plates in adjusted telescopic relation, and means on the plates adapted to engage the side walls of the drawer releasably for holding the follower in predetermined position within the drawer.
- 10 6. A follower block for a filing drawer, embodying a pair of rectangular plates in and extending transversely of the drawer, said plates being adapted to slide longitudinally towards and away from one another, means on the two plates adapted to coact in a manner to hold them against lateral separative movement, releasable means for holding the two plates against relative lon-
- gitudinal movement, and means on the plates adapted to engage the side walls of the drawer releasably for holding the follower in predetermined position within the drawer, said last mentioned means including an arm mounted on each plate for horizontal pivotal movement, each arm being forked at one end and the forked end of each arm being adapted to project beyond the free end of the associated plate when said arm is swung in a given direction, and springs adapted to urge said arms in said given directions.

In witness that I claim the foregoing I have hereunto subscribed my name this 9th day of July, 1925.

LYSANDER H. DODGE.
